UNITED STATES PATENT OFFICE

MARK ANTON, OF WEST ORANGE, NEW JERSEY, ASSIGNOR TO PIE BAKERIES OF AMERICA, INC., OF NEWARK, NEW JERSEY

RACK

Application filed May 1, 1929. Serial No. 359,499.

This invention relates to a rack for various articles but is particularly designed for display of articles that are to be repeatedly brought out and returned as in the sale of 5 pies. The rack is therefore primarily a pie rack. The object of the invention is to provide a rack that displays the goods but that can have its various trays or holders swung into or out of vertical alignment to allow inspection and cutting of the pies and then 10 quick and convenient return. Furthermore, the trays can be arranged out of alignment for symmetrical presentation as when the trays are swung to both sides of the centre 15 post which acts also to hold a card or tag at the top of the rack.

The invention is illustrated in the accompanying drawings in which Figure 1 is a side view of a rack made according to my invention. Figure 2 is a face view of the upper 20 part thereof and Figure 3 is a section on line 3—3 in Figure 1.

The rack comprises a base 10 which is usually round and is flat as it is formed of a fairly 25 heavy sheet metal and is extensive enough to hold the rack erect when it is filled.

The base serves to hold the post 11 which is arranged near one edge of the base in order to hold the trays or holders over the approximate center of the base. The trays 12 are 30 usually extended further at the bottom and extended less at the top. They include the arms 13 which are formed into eyes 14 which encircle the post 11. The eyes are spaced by 35 tubular sheet-iron spacers 15 and can swing on the rod to any horizontal position desired. The trays 12 can be arranged in a spiral formation, aligned vertically, staggered by being placed alternately on opposite sides of the 40 post or arranged in other relations, as desired. The trays can be swung from underneath the ones above to enable pies in them to be cut and they can then be returned to their positions.

45 This swinging from underneath the higher trays also allows inspection without handling which is much more sanitary than the present type of rack with its fixed shallow shelves and the consequent necessity of removing and 50 replacing pipes to find the kind wanted. In

addition to this the cleaning of the shallow shelves in the old form or rack is difficult and sometimes impossible when the crumbs of crust lodge in corners and recesses of the closet or rack.

The trays 12, in the present device, are 55 made of rings 16 which are welded or riveted to the divergent ends 17 of the arms 13. The wire strands 18 which span the open rings 16 form the bottom to support any 60 dishes or plates that fit inside the ring 16. The wires and rings and the arms are usually welded together to form a unitary device to be placed on the post 11.

The piece or display tag is placed at the top 65 and comprises a plate 19 with flanges 20 at the sides and bottom and with a socket or tube 21 secured at the back. This tube 21 is slid over the top of the assembled eyes and spaces 70 on the rod 11 and forms a top for these elements.

The post 11 is usually secured to the bottom 75 of the tray 10 by a nut 22 which can be inserted because the base is generally flanged slightly at the edges to space the major part of its area from the counter or table.

The assembling of this device is extremely 80 simple and the number of trays can be varied in the various racks according to the height of the post that is supplied.

I claim:—

A rack comprising a base, a post extending upwardly from the base, trays made of strip metal bent to form a ring and including arms formed of strip metal bent into a closed 85 loop at one end and having divergent ends secured to the trays, tubular spacers alternating with the closed loops of the arms and fitting on the post, and wires spanning the trays to form supports at the bottom thereof. 90

In testimony whereof I affix my signature.
MARK ANTON.
